Application May 29, 1937, Serial No. 145,496

19 Claims. (Cl. 209—144)

This invention concerns improved machines and methods for classifying the particles of a mass of previously pulverized material, whereby material of a predetermined particle size may be segregated from the mass and delivered from the machine, or material of several different particle sizes may be delivered from the machine separately and concurrently. The machine is not intended to have any pulverizing action, although it is recognized in some of the suggested forms minor and incidental pulverizing will occur.

In the present machine the mass of pulverized material after being introduced into the machine is caught in a rising vortex of gaseous media, such as air, and is whirled around in a classifying compartment at high speed, care being exercised to prevent any disturbing forces, eddy or other currents. The gaseous media and pulverized material may enter the classifying compartment in many different ways and thereafter, according to the present invention, is maintained in the vortex state by a high speed, smooth rotor which, together with an oppositely disposed concentric, stationary wall of the machine, defines a narrow, vertical, annular classifying space.

The centrifugal force of the vortex action on the particles effects the classification or sorting of the material in accordance with the differences in size and corresponding mass velocities of the various moving particles in the classifying zone. That is, the finer particles being of small mass are less affected by the centrifugal forces set up by the vortex action, and consequently rise at and near the inner periphery of the vortex to a place of exit adjacent the top of the machine. The larger particles are projected outwardly toward the outer periphery of the vortex during their rise in the classifying space between the rotor and the opposite wall, and the respective sizes rise to define heights or places along the outer wall according to their sizes, as will be more fully explained hereafter. Consequently, in addition to the very fine particles, it is possible to take out of the classifying chamber and collect particles of any larger size, or of different graded sizes, by suitably locating a tapping zone or zones vertically of the circumferential wall of the classifier. It is, accordingly, one object of this invention to provide means for efficiently effecting any or all of the above purposes.

The machine of this invention is capable of classifying various kinds of pulverized materials whether they be of uniform chemical characteristics, or are compounds, or various forms of

aggregates, etc. Furthermore, the classifier of this application may be used with various types of pulverizing machines.

The air or other gaseous media may be let into the machine from a place beneath the rotor, or near the bottom of the machine, and may also be induced to rise through the classifying chamber by means of a suitable fan adjacent the top of the machine, or by appropriate exhaust means connected to an outlet from the classifying chamber. However, care should be exercised that such devices do not disturb or agitate the smooth movement of the rising currents of air and entrained material. If desired, the material to be classified may also enter the machine with the air. As another instance, the material may be fed tangentially through the wall of the classifying chamber either with or without the necessary air to form the carrier. As a further example, a suitable mechanical feeding means, such as a screw conveyor may be used, in which case the air may be fed into the classifying chamber from the bottom or tangentially, or both, as may be found advisable in accordance with operating conditions and the particular materials to be dealt with.

By whatever means the material and air enter the classifying chamber, unless the material enters the machine with a sufficiently vortical motion and in substantial suspension in the air, it is quickly put into suspension and the air and mass of suspended particles caused to whirl by the action of the high speed rotor. In the drawing the rotor is provided at its lower end only with spaced apart vertical fins or other suitable means for originating the vortex.

It is another object of this invention to provide a classifier with vanes or similar means to initiate a vortex action, and a smooth rotor element for maintaining the vortex action.

It is still another object of this invention to provide a classifier of the above indicated character wherein the classification zone has uninterrupted, smooth, continuous currents of air and entrained material.

In some industries abrasive materials having particles of uniform size are required. This is the case in the manufacture of brake bands where the abrasive particles in some instances must approximate 30 microns. In other fields it is important that the material have no metal contamination as for example the cosmetics or food industries. In handling all these materials the parts of the machine may be protected as by having the moving and stationary walls of the

classifying chamber covered with resilient material such as rubber. The rubber increases what might be termed a skin-drag effect on the air with two results, first, reducing the wear on the walls and rotor parts, and, second, the rubber covered rotor will move more air, thereby increasing the vortex action, without setting up undesired undulating or eddy currents, all of which is conducive to speedy and accurate classification. Furthermore, the rubber facing of the stationary wall has a retarding action on the particles moving therealong and slows or stops their motion somewhat definitely, and also preventing the deflection and return of the particles to the vortex.

It is, therefore, a further object of this invention to provide rubber or other similar walls along the classification zone.

At times, to obtain accurate classification it may be desirable to connect two or more classifiers in series relation so that the material is returned one or more times through classifying zones for further grading. With this arrangement, the oversize and undersize particles are both eliminated to obtain a substantially uniform final product. Hence, it is a still further object of this invention to provide a method and arrangement of apparatus for accomplishing the above-mentioned result.

Various other objects and advantages of the invention will appear as the description proceeds, reference being made to the accompanying drawings, illustrating several practical embodiments of the invention, and in which—

Figure 1 is a vertical sectional view of a classifying machine constructed in accordance with the invention, parts being broken away to facilitate the illustration;

Fig. 2 is a horizontal cross sectional view taken in the plane of line 2—2 of Fig. 1;

Fig. 3 is a fragmentary view in vertical section of a classifying machine illustrating a modified form of device having a plurality of tapping points at the side of the machine, and also showing the application of rubber linings to the classifying chamber;

Fig. 4 is a view in vertical section of a portion of a classifying machine illustrating a modified form of tapping arrangement at the side of the classifier, and also showing one form of conveyor for feeding pulverized material to the machine;

Fig. 5 is a fragmentary view of a classifier constructed according to the invention and illustrating the approximate paths taken along the classification chamber by the various sizes of particles, the spiral portion of the paths being omitted; and

Fig. 6 is a diagrammatic illustration of apparatus for and method of subjecting the particles one or more times to the action of a classifying zone for further gradation.

Referring to the drawings, and more particularly to Figs. 1 and 2, the machine comprises in general a stationary, vertical, generally cylindrical casing or housing 10, a drum-like rotor 11 mounted on a vertical shaft 12 for concentric rotation in the housing at high speed, the shaft being mounted in top and bottom bearings 13 and 14 respectively. The elongated space 15 defined between the rotor 11 and the opposite wall of the casing 10 forms a classifying chamber or zone for the pulverized material, which may be continuously fed to this chamber in a variety of ways.

If desired, the pulverized material, together with a gaseous medium, such as air or steam, may be fed into the classifying chamber through the inlet opening 16 disposed tangentially of the annular space about the rotor 11. Air also may be fed into the classifying chamber 15 at the bottom of the rotor 11 through a central opening in a base plate 18 and through an annular air-seal opening 19 which communicates with the air supply through an inlet opening 20 in the base of the machine. The rotor 11 revolving at high speed sets up, or continues as the case may be, a vortex in the material-laden air. A fan 17 mounted at the upper end of the shaft 12, or an exhaust fan (not shown) connected to the machine outlets also may induce the particles of the material and the supporting air currents to rise in the chamber 15 during the whirling action of the vortex. In cases where the bottom feed of air is used the air will rise through the classification zone, and the fan 17 may be considerably reduced in proportions or eliminated.

In cases where pulverized material is fed into the classifier with insufficient force, etc., it becomes necessary to initiate the vortex action quickly and in sufficient intensity, and in other cases where it is desired to more quickly set up the vortex action in the classifying chamber, the lower portion of the rotor 11 may be provided with spaced blades or fins 21. These blades are secured to the face of the drum or rotor, and are tapered with the wide portion moving very close to the bottom 18.

In all of the embodiments of the invention described in this application the details of construction of the apparatus may be substantially the same as that shown in Fig. 1. There the casing 10 is provided with a cover plate 31, to which is fastened the upper bearing member 13, and a base 38 which also supports the lower bearing 14. The rotor 11 may be mounted on the shaft 12 through the medium of upper and lower annular heads 39 and 40, the upper head 39 being bolted at 41 to a collar 42 keyed as at 43 to the shaft 12. The rotor 11 is of sheet metal, such as polished Monel metal, and is mounted between the plates 39 and 40 so as to form a smooth unbroken surface, especially in the upper portion. The fan or air impeller 17 is also secured to the collar 42 by the bolts 41.

The shaft 12 may be driven by a pulley and belt drive 44 from a motor 45, or may be directly connected to the motor. For ordinary purposes a speed of about 300 feet per second at the periphery of the rotor has been found satisfactory, but this as well as the rate of air input and the feed of the material may be varied according to the material and sizes being classified and can be regulated readily to bring about the desired results hereinafter described.

The fan 17 is mounted in a discharge chamber separated from the classification chamber 15 by an annular plate 23 having a central opening 22 of less diameter than the rotor, the arrangement being such that undulations or irregular movements of the air due to the rotation of the fan blades will not be felt in the classification zone 15.

The plate 23 is spaced above the rotor top plate 39 to provide space 49 communicating with opening 22, the passage 49 being relatively narrow. Accordingly, owing to the confined space and the surface grip of the top face of the rotor head 39, there is set up an intensive centrifugal ac-

tion which opposes the movement of any larger particles that may find their way into the narrow passage 49. Thus the larger particles are kept out of or expelled from the passage 49 toward the outer wall of the classification chamber where they fall by gravity toward the bottom of the chamber. It will be apparent that by regulating the height of the classification zone and the other factors, a uniform classification can be had of the smallest of the pulverized particles supplied to the classifier, or, if desired, of all particles below a certain size.

Considering the bottom portion in more detail, the air-seal opening 19 is formed between the bottom edge of the annular head 40 and the base plate 18. Adjacent the opening 19 is a set of air-impeller blades 47 which function somewhat like an air pump to supply air evenly and under pressure all around the bottom of the classification chamber at the base of the fins 21. The number and spacing and shape of the blades 47 may be varied without affecting the efficient operation of the machine, and in some cases they may be eliminated, for instance, if the air were forced into the machine under pressure through the inlet 20.

The lower portion of the classification chamber below the major classification zone may be characterized by an outer wall inclined outward toward the bottom of the chamber as indicated at 48. This inclined wall cooperates with the outer edges of the blades 21 arranged at a slightly greater inclination to form a tapered annular space the effect width of which becomes narrower as it approaches the bottom. With this arrangement, the centrifugal forces acting on the particles are increased at the bottom of the chamber due to the narrowed chamber and also the increased peripheral speed of the bottom of the tapered blades 21. Hence, the larger or oversize particles of material, falling to the bottom by gravity, are more quickly eliminated from the vortex by being swept around adjacent the base plate 18 to the outer wall 48 of the classification chamber and thence out of the machine through the exit port 26. It may be noted that the somewhat conical wall 48 also tends to deflect downwardly the heavier particles thrown outwardly by the mid and upper portions of the blades 21, thereby further aiding the process of eliminating those particles from the machine. A reason for the taper and height of the blades 21 is to gradually reduce and finally eliminate from the classification zone elements producing disturbing pulsations in the material-laden air, after which final classification begins, as will now be described.

The approximate path of the particles is spirally upwardly while the classified position of a particle of given size is approximately represented by the vector line computed from the forces acting on the particle. Such forces include the mass-velocity of the particle according to the well known formula (MV^2) , which is a force in a horizontal direction, and the opposed forces, in a vertical direction, of gravity and the rising component resulting from the lifting action of the gaseous media on the particles in the vortex. During revolution of the rotor 11 the pulverized particles of material to be classified are set in rapid whirling motion and are thrown outwardly toward the casing 10 with different velocities according to their mass (MV^2) while the lifting action of the air or of the fans tends to raise the particles toward the top of the classifying cham-

ber, and the force of gravity tends to draw the particles downwardly. For a given set of conditions of speed of rotation, volume of aspirating air, and the effect of the forces noted above, the separation or stratification of the particles occurs along somewhat definite lines corresponding to different heights, along the inner wall of the casing 10 apparently determined by the vector line or resultant of the forces named above. This is diagrammatically illustrated in Fig. 5 for a number of particles of different microscopic sizes. For particles of 100 screen mesh, for example, there is a point on the outer edge of the vortex adjacent the wall of the casing where centrifugal force upon such particles is not sufficient to maintain the particle in suspension against the pull of gravity, and hence particles of that size will quickly mass and fall from that height.

The same action occurs for particles of 200 screen mesh size, and of 50 micron size for further examples, but the points of equilibrium of the forces for these and other smaller sizes are at higher levels along the wall of the classification chamber.

Insofar as it has been possible to determine at the present time it is believed that the various points of equilibrium and stratification of the particles may be computed by considering a particle of a given size under a definite set of conditions at the lower portion of the major classification zone, which point is designated by the letter R. A 100 screen mesh particle will move substantially along the path of line R-S, a 200 mesh particle along the line R-S¹, a 300 mesh size particle along the line R-S², a 400 mesh size along the line R-S³, a fifty micron particle the line R-S⁴, and so on progressively with the smaller particles following closely the periphery of the rotor 11 and passing through opening 22 in plate 23 and out of the machine through a port 24. A collector of any suitable construction can be connected to port 24 to collect the particles discharged therefrom.

It is apparent that at any one or more of the circumferential areas S, S¹, etc., the particles of the respective sizes may be taken out of the machine by providing suitable tapping ports around the casing 10. Accordingly, as illustrated in Figs. 1 and 5 a ring of tapping ports 25 (obviously shown exaggerated in size) may be provided to take out the particles at the S⁴ level which, in this example, are of the order of fifty microns.

With the exception of the smaller particles, at times termed "fines," which leave the machine through the port 24, the other sizes than the selected fifty micron size particles fall toward the bottom of the classification chamber, and are swept out of the machine through the tangentially disposed outlet 26.

The ports 25 communicate with one or more chamber 25' disposed about the casing 10 and having one or more depending discharged openings 25^a which in turn may be connected to a collector of appropriate design.

In cases where the smallest size of particles collected is larger than fifty microns, the height of the classification chamber may be shortened and the upper discharge including passage 49, fan 17, etc., will be proportional to remove from the classification chamber substantially all material smaller than the selected size.

As was stated above, several different sizes of material may be removed from the classifier si-

multaneously. One arrangement therefor is by providing a repetition of tapping ports 25 at different levels as shown in Fig. 3. It is clear that any suitable number of circles of such ports may be provided and that with this arrangement a number of different particle sizes may be collected at the same time from a single machine.

In Fig. 4 is shown a slightly different form of tapping construction involving the same general principles. In this example, the diameter of the upper part of the casing 10 is enlarged as indicated at 21. This increase in the width of the classifying space enables the particles to travel outwardly where gravity has a smaller MV^2 force to overcome, thus the desired particles more readily gravitate and find their way substantially straight downward and out of the machine through the port openings 29 to a place of collection or use at the outside of the machine. It will be seen that with this form of device all particles between the smallest, which escape through opening 22, and the size determined by the height of the lip 28, will be collected so that a mixture of graduated sizes will be available. Such mixtures are usable in a number of industries, of which the cement industry is one.

There is also shown in Fig. 4 a screw feed conveyor 30, provided with a suitable feed opening 31 and driven by any desirable means such as a belt and pulley 32, which is one arrangement that may be used for feeding the pulverized material to the classifier. This form of feed may be substituted for that described in connection with Fig. 1.

Returning to Fig. 3, it has been found advantageous in some instances to provide the rotor and the opposite wall of the classification chamber with facings of suitable material such as rubber. These facings are indicated in the drawing by the numerals 33 and 34, respectively. The lower portion of the rubber faced rotor also may be provided with rubber impellers or fins 35. The relatively rough surface (as compared to polished metal) thus provided on the rotor wall 11 has an increased skin-drag effect and sets more air in motion than the polished metal surface consequently increasing the vortex action and the centrifugal throw-out of the various particles according to their mass characteristics, while the stationary rubber facing 34 has a damping effect tending to stop the travel of the projected particles at the rubber surface, so that the desired stratification becomes sharply defined. The rubber facings also protect the parts of the classifier from wear and lengthen the life of the classifier, in which the increased skin-drag effect probably plays an important part.

Although not shown, it will be understood that any suitable form of regulator may be inserted in the air inlet opening 20 to thus control the amount of aspirating air admitted at the bottom of the machine. By so controlling the air the particle size delivered and collected can be determined because varying this factor varies the upward force acting against gravity, and the time the material remains in the classifier chamber.

To obtain a high degree of uniformity in particle size with material required in some industries, Fig. 6 illustrates diagrammatically one method and arrangement of apparatus for continuously obtaining accuracy in classification of materials. A pair of classifiers, of the general kind described above, are connected together in a manner such that oversize and undersize particles are definitely eliminated from the final

product. Unit A in Fig. 6, operating as any of the machines described above, has a circle of tapping ports 125 which discharge into the lower portion of the classifying zone of unit B. The particle size at ports 125 may be fifty microns as assumed above, but some particles of smaller size also may be ejected through ports 125. However, when that discharged material enters the B unit the desired fifty micron particle has now become the largest particle size in the B unit. That particle size may now be discharged and collected through bottom outlet 126 while the lighter material rises and is taken off at the top opening 136 or through an intermediate tap 137 as indicated.

While several practical embodiments of the invention have been illustrated and described, it is to be understood that various other modifications and changes may be made without departing from the fundamental principles outlined. Accordingly, it is not intended to impose limitations in the scope of the invention, except as defined in the appended claims.

I claim:

1. A machine for classifying pulverized material containing particles of different sizes, comprising a cylindrical casing, a cylindrical rotor within said casing and concentric with and spaced from said casing to form a classifying chamber therebetween which is narrow as compared to the diameter of said rotor, means for feeding the material and a gaseous medium to the classifying chamber, means for driving said rotor at high speed to maintain a vortex of said material in gaseous suspension, means for causing the suspended material to rise in the classifying chamber during the vortex action, and a tapping port at a definite level along the side of the casing through which particles of the suspended material of a predetermined size pass from said chamber.

2. A machine for classifying pulverized material containing particles of different sizes, comprising a cylindrical casing, a cylindrical rotor within said casing and concentric with and spaced from said casing to form a classifying chamber therebetween which is narrow as compared to the diameter of said rotor, means for feeding the material and a gaseous medium to the classifying chamber, means for driving said rotor at high speed to maintain a vortex of said material in gaseous suspension, means for causing the suspended material to rise in the classifying chamber during the vortex action, and tapping ports at different levels along the side of the casing through which particles of said material of predetermined different sizes pass from said chamber.

3. A machine for classifying pulverized material containing particles of different sizes, comprising a cylindrical casing, a cylindrical rotor within said casing and concentric with and spaced from said casing to form a classifying chamber therebetween which is narrow as compared to the diameter of said rotor, means for feeding the material and a gaseous medium to the classifying chamber, means for driving said rotor at high speed to maintain a vortex of said material in gaseous suspension, means for causing the suspended material to rise in the classifying chamber during the vortex action, an outlet at the top of the casing for removal of collectible fine particles of said material rising in said chamber adjacent the peripheral face of the rotor, and a tapping port at a definite level along

the side of the casing through which classified particles of said material of a size larger than said fine particles pass from said chamber.

4. A machine for classifying pulverized material containing particles of different sizes, comprising a cylindrical casing, a cylindrical rotor within said casing and concentric with and spaced from said casing to form a classifying chamber therebetween which is narrow as compared to the diameter of said rotor, means for feeding the material and a gaseous medium to the classifying chamber, means for driving said rotor at high speed to maintain a vortex of said material in gaseous suspension, means for causing the suspended material to rise in the classifying chamber during the vortex action, an outlet at the top of the casing for removal of collectible fine particles of said material rising in said chamber adjacent the peripheral face of the rotor, and tapping ports at different levels along the side of the casing through which classified particles of said material of larger sizes pass from the classification chamber.

5. A machine for classifying pulverized material containing particles of different sizes, comprising a cylindrical casing, a cylindrical rotor within said casing and concentric with and spaced from said casing to form a classifying chamber therebetween which is narrow as compared to the diameter of said rotor, means for feeding the material and a gaseous medium to the classifying chamber at one end thereof, means for driving said rotor at high speed to maintain a vortex of said material in gaseous suspension, means for causing the suspended material to rise in the classifying chamber during the vortex action, and a tapping port at a definite level along the side of the casing through which classified particles of material pass from said chamber, the classifying rotor being provided with impeller blades extending part way along said rotor adjacent said feeding means only.

6. A machine for classifying pulverized material containing particles of different sizes, comprising a cylindrical casing, a cylindrical rotor within said casing and concentric with and spaced from said casing to form a classifying chamber therebetween which is narrow as compared to the diameter of said rotor, means for feeding the material and a gaseous medium to the classifying chamber, means for driving said rotor at high speed to maintain a vortex of said material in gaseous suspension, means for causing the suspended material to rise in the classifying chamber during the vortex action, and a tapping port at a definite level along the side of the casing through which classified particles of said material pass from said chamber, said feeding means including an opening through the casing beneath said tapping port and a connecting conduit substantially tangential to said classifying chamber.

7. A machine for classifying pulverized material containing particles of different sizes, comprising a casing, a rotor concentric with and spaced from said casing to form therewith a classifying chamber, means for feeding the material and a gaseous medium to the classifying chamber, means for driving said rotor at high speed to maintain a vortex of said material in gaseous suspension, means for causing the suspended material to rise in the classifying chamber during the vortex action, a tapping port at a definite level along the side of the casing

through which classified particles of material pass from said chamber, said feeding means including an opening through the casing beneath said tapping port and a connecting conduit substantially tangential to said classifying chamber, and an exit opening in the periphery of said chamber and adjacent the lower end thereof from which gravitated material is swept from the machine by the action of the rotor.

8. A machine for classifying pulverized material containing particles of different sizes, comprising a casing, a rotor concentric with and spaced from said casing to form therewith a classifying chamber, means for feeding the material and a gaseous medium to the classifying chamber, means for driving said rotor at high speed to maintain a vortex of said material in gaseous suspension, means for causing the suspended material to rise in the classifying chamber during the vortex action, tapping ports at different levels along the side of the casing through which stratified particles of said material of predetermined different sizes pass from said chamber, said feeding means including an opening through the casing beneath all of said tapping ports and a connecting conduit substantially tangential to said classifying chamber, and an exit conduit substantially tangential to said chamber and beneath the plane of said other opening.

9. A machine for classifying pulverized material containing particles of different sizes, comprising a casing, a rotor concentric with and spaced from said casing to form therewith a classifying chamber, means for feeding the material and a gaseous medium to the classifying chamber, means for driving said rotor at high speed to maintain a vortex of said material in gaseous suspension, means for causing the suspended material to rise in the classifying chamber during the vortex action, tapping ports at different levels along the side of the casing through which stratified particles of said material of predetermined different sizes pass from said chamber, said feeding means including an opening through the casing beneath all of said tapping ports and a connecting conduit substantially tangential to said classifying chamber, and an exit conduit substantially tangential to said chamber and beneath the plane of said other opening.

10. A machine for classifying pulverized material containing particles of different sizes, comprising a casing, a smooth rotor having a smooth surface concentric with and spaced from said casing to form therewith a classifying chamber, an inlet for a gaseous medium at one end of said rotor and means communicating with the other end of the rotor so constructed and arranged that said medium rises through the classifying chamber, means for feeding the pulverized material to the chamber, means for driving the rotor at high speed to maintain a vortex action and to intermix said material with the gaseous medium to form a suspension of dispersed particles, and a port at the side of the casing communicating with the classifying chamber, said port being located at a point intermediate the ends of said rotor and being adapted for the withdrawal from said chamber of stratified material of a predetermined particle size.

11. A machine for classifying pulverized material containing particles of different sizes, comprising a casing, a smooth rotor having a smooth surface concentric with and spaced from said

casing to form therewith a classifying chamber, an inlet for a gaseous medium at one end of said rotor, means communicating with the other end of the rotor so constructed and arranged that said medium rises through the classifying chamber, means for feeding the pulverized material to the chamber, means for driving the rotor at high speed to maintain a vortex action and to intermix said material with the gaseous medium to form a suspension of dispersed particles, and ports at the side of the casing at different levels along the classifying zone so that stratified particles of predetermined particle sizes respectively may be removed from the classifying chamber.

12. A machine for classifying pulverized material containing particles of different sizes, comprising a cylindrical casing, a vertical, cylindrical rotor within said casing and concentric with and spaced from said casing to form a classifying chamber therebetween which is narrow as compared to the diameter of said rotor, an inlet for a gaseous medium at one end of said rotor and means communicating with the other end of the rotor arranged so that said medium rises through the classifying chamber, means for feeding the pulverized material to the chamber, means for driving the rotor at high speed to maintain a vortex action and to intermix said material with the gaseous media to form a suspension of dispersed particles, a port at the side of the casing communicating with the classifying chamber, said port being located at a point intermediate the ends of said rotor and being adapted for the withdrawal from said chamber of stratified material of a predetermined particle size, said casing having an outlet port above the rotor, and a plate adjacent the top of the rotor interposed between said outlet port and the classifying chamber, said plate having an opening for passage of relatively small and collectible particles from the classifying chamber to said outlet port, said plate defining a restricted passage with the top of the rotor arranged to set up a centrifugal action in said passage to oppose entry therethrough of stray particles of relatively larger sizes.

13. A machine for classifying pulverized material containing particles of different sizes, comprising a cylindrical casing, a vertical, cylindrical rotor within said casing and concentric with and spaced from said casing to form a classifying chamber therebetween which is narrow as compared to the diameter of said rotor, an inlet for a gaseous medium at one end of said rotor, means communicating with the other end of the rotor arranged so that said medium rises through the classifying chamber, means for feeding the pulverized material to the chamber, means for driving the rotor at high speed to produce and maintain a vortex action and to intermix said material with the gaseous media to form a suspension of dispersed particles, the lower peripheral portion only of said rotor being provided with impeller blades to initiate the vortex action, the lower portion of the casing adjacent said blades being inclined inwardly and upwardly.

14. A machine for classifying pulverized material containing particles of different sizes, comprising a cylindrical casing, a vertical, cylindrical rotor within said casing and concentric with and spaced from said casing to form a classifying chamber therebetween which is narrow as compared to the diameter of said rotor, an inlet for a gaseous medium at one end of said rotor, means communicating with the other end of the rotor

arranged so that said medium rises through the classifying chamber, means for feeding the pulverized material to the chamber, means for driving the rotor at high speed to produce and maintain a vortex action and to intermix said material with the gaseous media to form a suspension of dispersed particles, the lower portion only of said rotor having inwardly and upwardly tapered impeller blades, and the lower portion of said casing being similarly tapered.

15. A machine for classifying pulverized material containing particles of different sizes, comprising a cylindrical casing, a vertical, cylindrical rotor within said casing and concentric with and spaced from said casing to form a classifying chamber therebetween which is narrow as compared to the diameter of said rotor, an inlet for a gaseous medium at one end of said rotor, means communicating with the other end of the rotor arranged so that said medium rises through the classifying chamber, means for feeding the pulverized material to the chamber, means for driving the rotor at high speed to produce and maintain a vortex action and to intermix said material with the gaseous media to form a suspension of dispersed particles, the lower portion only of said rotor having upwardly and inwardly tapered impeller blades, the lower portion of said casing being also upwardly and inwardly tapered to cooperate with said blades, and a discharge opening opposite said blades.

16. A machine for classifying pulverized material containing particles of different sizes, comprising a cylindrical casing, a vertical, cylindrical rotor within said casing and concentric with and spaced from said casing to form a classifying chamber therebetween which is narrow as compared to the diameter of said rotor, means for feeding the material and a gaseous medium to the classifying chamber, means for driving said rotor at high speed to maintain a vortex of said material in gaseous suspension, means for causing the suspended material to rise in the classifying chamber during the vortex action, and a tapping port at a definite level along the side of the casing through which stratified particles of material pass from said chamber, the portion of said casing above the level of said port being enlarged and communicating therewith.

17. A machine for classifying pulverized material comprising a stationary cylindrical casing, a concentric smooth walled cylindrical rotor within said casing and spaced therefrom a distance which is small as compared to the diameter of the rotor, resilient covering material upon opposed faces of said casing and rotor, means for feeding a gaseous medium and pulverized material to the space between the casing and rotor, outlets respectively for material of selected size and for oversize material, and blades constructed at least in part of resilient material cooperating with said rotor to produce and maintain a vortex action in the pulverized material and gaseous medium and to eject oversize particles of material.

18. A machine for classifying pulverized material comprising a stationary cylindrical casing having a smooth inner surface, a concentric cylindrical rotor within said casing and spaced radially therefrom a distance which is small as compared to the diameter of said rotor, said rotor having a smooth wall except for a bladed portion at one end thereof, a rubber covering for the inner surface of the casing and for the opposed surface of the rotor, means for feeding material

to the space between the rotor and casing, an outlet from said space adjacent the end of the rotor opposite said bladed portion, and means for producing a current of air through substantially the entire extent of said space and through said outlet.

19. A machine for classifying pulverized material comprising a stationary cylindrical casing having a smooth inner surface, a concentric cylindrical rotor within said casing and spaced 10 radially therefrom a distance which is small as

5 compared to the diameter of said rotor, said rotor having a smooth surface opposite said inner surface, a rubber covering for the inner surface of the casing and for the opposed surface of the rotor, means for feeding material to the space between the rotor and casing, an outlet from said space adjacent the end of the rotor opposite said bladed portion, and means for producing a current of air through substantially the entire extent of said space and through said outlet.

HENRY G. LYKKEN.
